RAILWAY TRUCK SPRING

Percy R. Drenning, Baltimore, Md., assignor to
 T. H. Symington & Son., Inc., Baltimore, Md., a
 corporation of Maryland

Application November 6, 1931, Serial No. 573,470

5 Claims. (Cl. 267—4)

The invention relates to resilient load sustaining means and has special reference to spring suspension or supporting means for the bolsters of railway car trucks and the like.

5. The principal object of the invention, generally stated, is to provide a novel spring combination and arrangement calculated to provide easier riding qualities under light load conditions, to increase the total spring capacity, and to prevent 10 the usual objectionable "jiggle" or vertical oscillation which, if permitted to build up, may become of such amplitude and violence as to throw the bolster off the springs.

It is known that with the ordinary spring construction involving a nest, cluster or assembly of either single or double coil springs, or a combination of both, all of the same height, travel and capacity, the spring resistance is too stiff under light loads or, if proper under light loads, insufficient in capacity to take care of the maximum loads. Furthermore as the ordinary springs are usually of the same character as regards height, travel and capacity they all naturally have the same or substantially the same period of vibration 25 and the result is that the inevitable vertical oscillation builds up when synchronized with the shocks or jars caused by passage of the car wheels over the rail joints to such an extent that the truck bolster moves up and down upon the springs with such amplitude of vibration that the bolster may be thrown off, resulting in unloading of the wheels and possible consequent derailment, not to mention the tremendous damage done particularly to perishable and fragile goods.

35. It is with the above facts in view that I have devised the present invention which has for an important object the provision of a novel truck spring assembly embodying spring elements or units of different types so as to obtain all the 40 benefits of the easy riding qualities of elliptical springs, in addition to increasing the total capacity and breaking up jiggle, the latter being accomplished owing to the fact that the springs of different types have different respective periods 45 of oscillation and will consequently act as a check one upon another.

Another object of the invention is to provide a spring assembly embodying a combination of helical springs and pairs of semi-elliptic springs so 50 arranged, connected and related as to constitute and perform the function of full elliptic springs.

Another object is to provide an assembly of this character in which the initial load comes upon the elliptic spring means so that they will be partially compressed before the helical springs are

deflected, this being advantageous on account of the superior riding qualities of elliptic springs, at least under light load conditions.

Another important object of the invention is to provide a spring assembly of this character which may be made to replace the ordinary or accepted standard type of nest without involving any changes whatsoever in the construction of the truck in which it is used.

A further object is to provide a spring having novel means for centering the helical and elliptic spring means with respect to one another, a part of this centering means also operating to maintain the entire assembly in proper position with respect to the side frames and truck bolster.

A still further object is to provide an assembly of this character which may be constructed as a complete and separate entity and handled as such so as to be capable of installation as a replacement for a standard nest without involving manipulation of the individual parts at such time, the entire structure being held in assembled relation by tie members and prevented from shifting by cooperative engagement of means on the assembly with the holes or recesses commonly provided in the spring seat or bolster.

An additional object is to provide a spring assembly which will be simple and inexpensive to make, easy to install, positive in action, efficient and durable in service, and a general improvement in the art.

To the attainment of the foregoing and other objects and advantages, the invention preferably consists in the details of construction and the arrangement and combination of parts to be 90 hereinafter more fully described and claimed, and illustrated in the accompanying drawing in which:

Figure 1 is a plan view of a truck spring assembly constructed in accordance with my invention.

Figure 2 is a view partly in side elevation and partly in section taken on the line 2—2 of Figure 1, and

Figure 3 is a partial cross sectional view taken 100 on the line 3—3 of Figure 1, parts being in elevation.

Referring more particularly to the drawing, I have shown the assembly as comprising similar upper and lower caps 10 between which are interposed helical spring units 11 of any desired diameter and formed of suitable sized stock depending upon the necessary capacity. In the present instance these units are represented as single coils which may be of the A. R. A. stand- 105 110

ard type though it should be distinctly understood that there is no particular limitation in this respect as double coils might be used if found preferable, this being also a matter depending upon the contemplated capacity of the entire assembly.

The means for maintaining the helical spring units in proper position between the caps might of course be varied, or in other words different 10 expedients might possibly be resorted to but I prefer to employ ties 12 passing through stamped-out curved projections 13 fitting within the ends of the springs.

In addition to the helical units, I make use of 15 pairs of semi-elliptic springs 14 disposed in confronting or superposed relation and so connected as to define elliptic springs. Each semi-elliptic spring is provided centrally with the usual type of encircling band 15 which acts to hold the 20 plates or leaves assembled and against lateral displacement. Any known or preferred means may be provided for preventing relative longitudinal movement of the spring leaves but as co-acting humps or "buttons" or the like for such 25 purposes are so well recognized nothing of the sort is illustrated. The opposite sides of the spring caps 10 are notched or recessed inwardly as at 16 for the reception and accommodation of the bands 15 so that the elliptic units will 30 be properly disposed with relation to the remainder of the assembly. It is intended that the stock from which the bands 15 are formed be of sufficiently greater thickness than the thickness of the spring caps that the bands will project 35 beyond the outer surfaces of the caps so that when the assembly is installed within a truck and the bolster let down the elliptic springs will be initially compressed for a portion of their travel, that is to say they will be deflected to a certain extent before the helical units become 40 energized.

For connecting the ends of the pairs of semi-elliptic springs so that full elliptic spring means will result, I provide tie members 17 which may 45 conveniently be formed as castings and which extend across the space between the pairs of semi-elliptic springs, the tie members being formed at their ends with pockets 18 which receive curved extensions 19 on the ends of the innermost or 50 master leaves 20. The pockets are preferably formed with openings 21 to permit the escape of any water which might otherwise accumulate.

For maintaining the entire structure in assembled position in the truck the bands 15 are 55 formed with stamped-out projections 22 fitting within the holes or recesses commonly provided in the spring seat and bolster for association and engagement by the projections on nests of usual variety.

Owing to the fact that the caps are connected by the ties 12 and the fact that the ends of the semi-elliptic units are connected by the transverse ties 17 with the bands 15 received within the recesses or notches 16, and the further feature that 60 the caps carry the curved projections 13 fitting within the helical units, it will be apparent that all of the elements of the assembly will be held positively in proper position so that displacement of any part in any direction will be prevented.

In effecting installation, it is merely necessary that the truck bolster be jacked up so that the assembly may be slipped into place within the window opening and of course properly positioned therein to bring the projections 22 which project

from the lower cap into engagement within the holes or recesses provided for their reception in the spring seat, the projections on the upper cap then naturally taking a position in alinement with the corresponding holes or recesses in the underside of the bolster. The bolster is then let down upon the assembly.

In the operation, it will be seen that when the assembly is installed as above described and the weight of the bolster and the load comes upon it the elliptic units 14 are initially compressed, the travel equaling the degree of projection of the bands 15 beyond the caps. The helical spring units 11 are then of course also deflected. After the initial compression of the elliptic springs prior to energization of the helical units, it will be apparent that as the load is increased the elliptic springs will be deflected in parallel with the helical springs. In service it will be understood that as the elliptic springs have a different natural period of vibration from that of the helical units, each type of spring will act as a check upon the other so that there will be no synchronization of vibration, thereby avoiding the building up of the vertical oscillations or destructive joggle.

Another feature of advantage is that the ultimate capacity of the assembly is far greater, or can be readily made much greater, than that of the ordinary spring nest wherein single, double, or a combination of both, helical coils are provided. It is of course understood that the matter of dimensions and capacity of the assembly in so many pounds is not an essential feature of the invention as there is such a wide field for variation. However, reference may be had to my co-pending application for patent for Railway truck springs, filed September 16th, 1931, Serial No. 563,189, for a disclosure regarding dimensions, capacity of the individual units, etc. Attention is, however, directed to the fact that in this assembly the capacity of the elliptic spring means is large when compared with the total capacity and may readily be as much as a third. This high proportion of elliptic spring capacity with respect to the total capacity is of great advantage as 110 springs of the elliptic type possess easy riding qualities and their presence in the assembly will prevent any stiffness of action under light loads. At the same time the increase in the total capacity as compared with that of the standard type of 115 nest will take care of even the heaviest loads so that there will be no danger of over-stressing any of the units. The feature of the elimination of 120 joggle has already been discussed and it is consequently believed that from the foregoing the construction, operation and advantages will be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. In a railway truck spring assembly, spring 145 caps, means connecting the caps for limiting separating movement, a plurality of helical spring units interposed between the caps, a plurality of pairs of semi-elliptic springs interposed between the caps and located at opposite sides of the heli- 150

- cal springs, transverse ties bridging the space between the pairs of semi-elliptic springs and having their ends formed with pockets, said semi-elliptic springs including master leaves having 5 downturned ends fitting within pockets in said transverse ties, whereby the semi-elliptic springs will function as full elliptic springs, a band encircling the intermediate portion of each semi-elliptic spring, and projections on said bands 10 adapted to center the assembly in a truck. 2. A railway truck spring assembly comprising spring caps, helical spring means interposed therebetween, elliptic spring means interposed between the caps, means tying the caps 15 together, center bands carried by the elliptic spring means engaging said caps, means adapted to confine the elliptic spring means to the assembled caps and helical spring means, and projections on said bands extending beyond the caps 20 adapted to center the assembly in a truck. 3. In a railway truck spring assembly, spring caps, means connecting the caps for limiting separating movement, a plurality of helical spring units interposed between the caps, a plurality 25 of pairs of semi-elliptic springs interposed between the caps and located on opposite sides of the helical springs, transverse ties connecting the semi-elliptic springs of each pair together and with the other pair whereby they will function as full elliptic springs, a band encircling the intermediate portion of each semi-elliptic spring, and projections on said band adapted to center the assembly in a truck. 4. A railway truck spring assembly comprising upper and lower spring caps, helical spring means and an elliptic spring having center bands disposed between said caps and arranged to operate in parallel under the applied load, the load surfaces of the helical spring means contacting with the inner surfaces of the caps and said center bands engaging said caps, and projections on said bands adapted to center the assembly in a truck. 5. A railway truck spring assembly comprising upper and lower spring caps, helical spring means and an elliptic spring having center bands disposed between said caps and arranged to operate in parallel under the applied load, the helical spring means and elliptic spring being positioned by the caps, and projections on the bands adapted to center the assembly in a truck.
